UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

ELECTRICAL FEELER IN LOOM TRANSFERRER ARM.

Application filed November 26, 1926. Serial No. 150,696.

This invention relates to improvements in weft detectors for filling changing looms and it is the principal object of the invention to provide a detector employing an electrical circuit part of which is located on a regularly moving transferrer arm.

In certain types of looms, such as those shown in patent to Ryon No. 1,372,316, the transferrer arm is given a downward movement toward the bobbin on each detecting beat of the loom. As heretofore constructed these transferrers have been provided with mechanically or pneumatically operating detectors which, under certain conditions, are found not to be as sensitive as desired. It is an important object of my present invention to provide a transferrer arm with yielding plungers or similar devices electrically connected to an electric circuit for the purpose of controlling an indicating element.

It is a more specific object of my invention to provide a regularly moving transferrer arm with an electro-magnet and a plunger releasing detent, said latch having an armature to be attracted by the electro-magnet to release the plunger when the yarn in the active shuttle has been depleted sufficiently to permit metallic contact between a portion of the bobbin and a portion of the electric circuit carried on the transferrer arm.

Transferrer arms for looms of the type specified have a quick downward movement toward the bobbin to detect the condition of the filling and the arm also has an upward movement which cooperates with bobbin releasing devices forming a part of the multi-color replenishing mechanism. It is desirable to prevent a closing of the electric circuit while the transferrer arm is in its upper position, even though the contact parts thereof are electrically connected. Accordingly, it is a further object of my invention to provide an additional means for opening the circuit when the transferrer arm is in upper position.

With these and other objects which will appear as the description proceeds, my invention relates to the arrangements and combinations of parts hereinafter set forth, and more particularly pointed out in the claims.

In the accompanying drawings, wherein a

convenient embodiment of my invention is shown

Fig. 1 is a diagram showing a transferrer arm and actuating mechanism therefor having my invention applied thereto,

Fig. 2 is a view similar to a portion of Fig. 1 on an enlarged scale, with the arm in a different position,

Fig. 3 is a detail top plan taken in the direction of arrow 3, Fig. 2,

Fig. 4 is an enlarged rear elevation taken in the direction of arrow 4, Fig. 2,

Fig. 5 is an enlarged vertical section on line 5—5 of Fig. 2,

Fig. 6 is a detailed vertical section on line 6—6 of Fig. 4, and

Fig. 7 is a horizontal section on line 7—7 of Fig. 5.

Referring to Fig. 1 the loom frame 10 supports a weft replenishing mechanism 11 more particularly of the multi-color type and having a transferrer arm 12 pivoted as at 13. A vertical rod 14 attached as at 15 to the transferrer arm is connected at the lower end thereof to a rocking lever 16, the rear of which is provided with a ball 17. The latter is received by a groove 18 formed in a cam 19 which rotates about shaft 20. Said shaft may be the bottom shaft of the loom and rotates once every second pick of the loom so that the transferrer arm completes its cycle in two picks.

As shown in Figs. 4 and 5, that portion of the transferrer arm indicated at 21 which lies over the bobbin B has slidably mounted thereon a plunger 22 which is normally held in non-indicating position by a latch 23 pivoted to the transferrer arm at 24 and counter weighted so as to lie normally in the position shown in Fig. 4. The plunger extends through a web 25 and has a head 26 which is held by a hook of the latch 23. A compression spring 27 is interposed between the web 25 and the indicating head 28 of the plunger and tends to move the latter to the indicating position shown in Fig. 5 whenever the latch 23 is raised. As the transferrer arm is raised with the plunger 22 in the position shown in Fig. 5 the indicator head 28 will cooperate with parts, not shown herein but set forth in the aforesaid patent to give the replenishing mechanism an initial

movement preparatory to transfer. The matter thus far described is of common construction and forms no part of my present invention.

In carrying out my improvements I provide each of the bobbins B with a metallic ferrule 40 normally covered by yarn as indicated in Fig. 4, but which upon substantial exhaustion of weft will be uncovered. I further provide the transferrer arm with a pair of contact plungers 41 and 42, respectively, each having a shoulder 43 which receives the downward thrust of a compression spring 44. The plunger 41 is guided by and has direct electrical contact with a cap 45 secured to the transferrer arm as shown in Fig. 6. Plunger 42 is insulated from the transferrer arm and slides in upper and lower bearings 46 and 47, respectively, made of fibre or other insulating material. The compression spring of plunger 42 lies between the bearings 46 and 47 so as to be electrically insulated from the transferrer arm.

In order to control the latch 23 I provide the same with a depending arm 48 normally resting against a pin 49 in the transferrer arm and having the lower end thereof formed as shown in Fig. 7 with an offset armature 50. The latter is formed of magnetic material and is normally spaced from the core 51 of an electro-magnet 52 held to the transferrer arm in fixed position, as shown in Fig. 5.

As shown more particularly in Figs. 2 and 3 a bracket 53 formed of insulating material is mounted on the transferrer arm and supports a spring contact member 54. A stationary spring contact member 55 is secured to and insulated from the frame 10 of the loom and is so placed as to have contact with the member 54 when the transferrer is down and spaced therefrom when the transferrer arm is raised.

The devices are electrically connected by having one end of a wire 56 secured to shoulder 43 of plunger 42, and the other end thereof connected to the magnet 52. The other side of the magnet is connected by wire 57 to the bracket 53 and member 54. The spring member 55 is connected by wire 58 to one side of a battery 59 the other side of which is grounded to the loom frame by wire 60.

As the transferrer arm reaches the lower limit of its movement on a detecting pick the members 54 and 55 will be brought into electrical contact, but so long as ferrule 40 is covered no current will flow as the plungers are electrically disconnected. When the weft is depleted, however, and both plungers are in metallic contact with ferrule 40, the current will pass from battery 59 through wire 58, contact members 55 and 54, respectively, bracket 53, wire 57, electro-magnet 52, wire 56, plunger 42, ferrule 40 to plunger 41. The latter, being grounded to the loom frame, closes the circuit so that current will flow

around core 51 and the armature 50 will be attracted, moving the latch to the position shown in Fig. 5, thereupon releasing plunger 22 so that spring 27 may move the same to indicating position.

As soon as the transferrer arm is raised the circuit is broken at two points, i. e. the plungers leave the ferrule and the members 54 and 55 separate. The armature 50 will therefore be released so that as the plunger 22 is returned to normal position on the continued upward movement of the transferrer arm, the latch 23 will be free to engage the head 26.

From the foregoing it will be seen that I have provided a regularly moving transferrer arm with a portion of an electrical circuit which is closed at the time of weft depletion to effect indication of weft exhaustion. Furthermore, it will be seen that the circuit is broken at two points when the transferrer arm is raised, so that accidental closing of the gap across the plungers will not operate to release the plunger 22 with the transferrer arm raised, because of the fact that members 54 and 55 are out of contact with each other. While I have shown the electromagnet as mounted directly on the transferrer arm, and have shown two bobbin engaging elements to close the circuit at the time of weft exhaustion, yet I do not wish to be limited to these constructions, as I believe I am the first to effect indication of weft exhaustion in a filling changing loom by a circuit which is closed by the movement of a transferrer arm.

Having thus described my invention and the advantages thereof, I do not wish to be limited to the details herein disclosed, otherwise than as set forth in the claims, but what I claim is:

1. In an electrical weft detector for looms operating with bobbins having an electric current conducting portion normally covered by weft, a normally open electric circuit including a source of power and member to be energized by electric current to indicate weft exhaustion, said electric circuit normally having two gaps therein, a transferrer arm having a movement toward the surface to be detected on each detecting beat of the loom, means carried by the transferrer arm to close one of the gaps in the circuit on each detecting beat of the loom, and additional means carried by the transferrer arm to have contact with the electric current conducting portion of the bobbin on indicating beats of the loom, whereby the other gap of said circuit will be closed at exhaustion of weft to energize the member.

2. In an electrical weft detector for looms operating with bobbins having an electric current conducting portion normally covered by weft, a transferrer arm having a movement toward the bobbin on each detecting beat of the loom, an electric circuit including a source of power, and an electrical

- device to be energized when the current flows through the circuit to control indication of weft exhaustion, said circuit being normally open at two points, and means carried by the transferrer arm to close the opening in the circuit at one of the points on each detecting beat of the loom and to close said circuit at both the points when the said conducting portion is uncovered.
- 5 3. In an electrical weft detector mechanism for looms operating with bobbins having an electric current conducting portion normally covered by yarn, a transferrer arm having a regular movement toward the bobbin on detecting beats of the loom, a spring pressed plunger mounted on the transferrer arm and normally held in non-indicating position, an electro-magnet mounted on the transferrer arm and controlling the plunger, an electric 10 circuit including a source of power and the electro-magnet detecting elements mounted on the transferrer arm and electrically connected to said circuit, said detecting elements being electrically connected together when 15 weft is depleted to such an extent that said elements may have contact with the electric current conducting portions of the bobbins to close the circuit to energize the magnet.
4. In an electrical weft detecting mechanism for looms, a transferrer arm having a regular movement toward the surface to be detected on each detecting beat of the loom, an electrical weft detector mounted on the transferrer arm, to be brought in contact 20 with the surface to be detected each detecting
- 25
- 30
- 35

beat of the loom, an indicating device, an electric controller for said device, and an electrical circuit including the detector and controller and adapted to be closed at weft exhaustion by the transferrer arm as the same moves toward the surface to be detected.

5. In an electrical weft detector for looms, a transferrer arm having a regular movement toward the surface to be detected, an indicating device, an electric controller for said device, an electric circuit including a source of power and said electric controller, and a detecting element in the circuit and mounted on said transferrer arm and carried toward the surface to be detected by the transferrer arm to close the circuit at substantial exhaustion of weft, at such times only as the transferrer arm is in down position.

6. In an electrical weft detector for looms, a normally open electric circuit, an indicating device effective to indicate when the circuit is closed, an electric controller for the device included in the electric circuit, a transferrer arm movable toward the surface to be detected, and means carried by the transferrer arm to close the circuit at weft exhaustion as the transferrer approaches the surface to be detected to actuate said controller for the indicating device.

In testimony whereof I have hereunto affixed my signature.

RICHARD GREENLEAF TURNER.
